DIAPER

Alexander H. Sonnenberg, East Elmhurst, N. Y.,
assignor of one-half to Walter J. Norris, Corona,
N. Y.

Application March 23, 1939, Serial No. 263,580

1 Claim. (CL. 128—284)

This invention relates to infants' wear. More particularly my invention relates to an improved construction of diapers adapted for use for infants.

One of the objects of my invention is to provide an improved diaper construction of the character described, which may be readily adjusted to the bodies of infants of varying physical characteristics and size, and which at the same time shall be attachable without the use of pins or similar fastening means.

Another object of my invention is to provide an improved diaper construction of the character described which shall have incorporated therein an infant's abdominal support or band.

Still another object of my invention is to provide a diaper construction of the character described which shall be relatively inexpensive to manufacture and which shall be extremely simple and effective in use and which, at the same time, shall be a general improvement in the art.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible embodiments of this invention,

Fig. 1 is a plan view of a diaper constructed in accordance with my invention and shown in fully opened position.

Fig. 2 is a cross sectional view taken substantially on the line 2—2 of Fig. 1;

Fig. 3 is a perspective view of reduced size, illustrating the manner of folding the diaper shown in Fig. 1; and

Fig. 4 is a perspective view illustrating the Fig. 1 form diaper in made up condition.

Referring now in detail to the drawing, there is disclosed in Figs. 1 to 4 a diaper constructed in accordance with my invention and designed to be made up and used without the necessity of employing pins or other similar fastening devices which may cause discomfort and harm to the infant.

In accordance with my invention, the diaper 10 may comprise a longitudinal rectangular-shaped piece of material 11. The material may be of the type generally employed for diapers, having the necessary absorbent and soft qualities. Extending outwardly from the opposite longi-

tudinal edges of the material 11 and disposed adjacent one transverse edge thereof are a pair of extensions 12 and 14, which may be of the same material as that of the part 11. The extensions 12 and 14 may be attached to the part 11 by any suitable means, such as the stitching 15. In Fig. 1 of the drawing, the diaper 10 is shown with the wrong side uppermost in order to facilitate the description thereof, but it is understood that in actual use the material 11 is placed with the opposite surface uppermost. Fixed to each of the extensions 12 and 14 at a point midway between the stitching line 15 and the edges 12a and 14a is a tape member 16 to which there is fixed a plurality of loop members 17 arranged in any suitable manner, such as by the row of stitching 18. It is noted that the loop members 17 are disposed in a direction away from the diaper part 11.

At a predetermined point from the top edge 11a of the part 11 there is fixedly attached substantially at the center of the width of the part 11 a pair of tapes 19 and 20. The tapes may be attached to the part 11 by any suitable attaching means, such as the stitching 21 and 22 respectively. The tapes 19 and 20 are made longer than the width of the part 11 so as to extend on opposite sides thereof for the purpose which will soon become apparent.

In use, the diaper 10 is positioned so that the loops 17 and the tapes 19 and 20 are underneath the surface of the diaper. In other words, in the position opposite to that shown in Fig. 1. The part 11 is first folded substantially in half on the transverse fold line 25, after which the already folded material may again be folded substantially in half on the transverse fold lines 26 providing four layers of material. Thus the diaper may be considered as comprising (1) a body portion which includes that part of the material 11 from the line 25 to the top edge 11a, and (2) a downward prolongation which includes the rest of said material. The transverse center of the body portion is at the upper line 26. When this has been done, the diaper appears as shown in Fig. 3 of the drawing, with the tabs 19 and 20 uppermost and exposed. The loops 17 of the extensions 12 and 14, however, are still adjacent the under surface of the tabs 12 and 14 as shown in Fig. 3.

Before making the second transverse fold as above described, the infant is placed in position on the once folded fabric in the customary manner, so that after the second fold on the transverse fold lines 26 is made, two layers of

material will be underneath and over the infant. The extensions 12 and 14 are then brought inwardly towards each other at the same time encircling the abdominal portion of the body of the infant and the tapes 18 and 20 passed through the loops 17 in any suitable arrangement, after which they may be tied as shown in Fig. 4 of the drawing. It is thus seen that I have provided a diaper construction in which the same may be attached without the use of pins or similar fastening devices and in which, at the same time, the fastening means employed, namely the extensions 12 and 14 serve to provide an abdominal supporting band for the infant, thus obviating the necessity of employing an additional band for this purpose, which has heretofore been the practice.

While in the drawing I have illustrated the use of two tieing tapes 18 and 20, it is understood that my invention may be satisfactorily practiced with only a single tape, or if desired the tapes may be entirely unattached and threaded in the cooperating loops after the diaper has been properly folded and adjusted.

It will thus be seen that there is provided a device in which the several objects of the invention are achieved, and which is well adapted to meet the conditions of practical use.

As various possible embodiments might be made

of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

A diaper comprising a textile body portion 10 which is transversely wider at the top than at the center; a straight parallel side edged central downward prolongation of like material extending from the bottom of said body portion; approximately of the same length as the body portion but of a substantial width not in excess of the narrow central part of said body portion, the diaper being adapted for placement, after retroversion of the prolongation inwardly upon the body portion to provide a double thickness of material, vertically about the crotch of the wearer with the upper half of the body portion at one side of the wearer's body and the lower half at the other side of the wearer's body, and with the legs protruding at opposite sides of the fold incidentally formed; and means for securing the diaper against displacement around the waist of the wearer.

ALEXANDER H. SONNENBERG.
